DESIGN FOR A COLLAPSIBLE CRIB

Althea W. Kunz, Minneapolis, Minn.

Application March 10, 1947, Serial No. 137,498

Term of patent 7 years

(Cl. D5—5)

To all whom it may concern:

Be it known that I, Althea W. Kunz, a citizen of the United States, residing at Minneapolis, in the county of Hennepin and State of Minnesota, have invented a new, original, and ornamental Design for a Collapsible Crib, of which the following is a specification, reference being had to the accompanying drawing, forming part thereof.

Fig. 1 is a side elevational view of a collapsible crib, showing the new design;

Fig. 2 is a top plan view;

Fig. 3 is an end elevational view;

Fig. 4 is a perspective view; and

Fig. 5 is an end elevational view showing the end of the collapsible crib opposite that disclosed in Fig. 3.

I claim:

The ornamental design for a collapsible crib, as shown.

ALTHEA W. KUNZ.
